UNITED STATES PATENT OFFICE.

ROBERT F. SLATER, OF ST. PAUL, MINNESOTA.

BAGGAGE-ROLLER.

No. 913,777.

Specification of Letters Patent.

Patented March 2, 1909.

Application filed December 21, 1907. Serial No. 407,587.

To all whom it may concern:

Be it known that I, ROBERT F. SLATER, a citizen of the United States, residing at St. Paul, in the county of Ramsey and State of Minnesota, have invented new and useful improvements in Baggage-Rollers, of which the following is a specification.

This invention relates to baggage rollers, and the object thereof is to provide a device, 10 in a manner as hereinafter set forth, particularly adapted for facilitating the loading of trunks, boxes, etc.; furthermore the device is so set up that it can be utilized as a truck for shifting or moving heavy burial 15 caskets or boxes.

Further objects of the invention are to provide a baggage roller which shall be simple in its construction, strong, durable, efficient in its use, readily set up and inexpensive to manufacture.

With the foregoing and other objects in view, the invention consists in the novel construction, combination and arrangement of parts hereinafter more specifically described 25 and illustrated in the accompanying drawings wherein is shown the preferred embodiment of the invention, but it is to be understood that changes, variations and modifications can be resorted to which come within 30 in the scope of the claim hereunto appended.

In the accompanying drawings, wherein like characters denote corresponding parts throughout the several views—Figure 1 is a top plan view of a baggage roller in accordance with this invention, and, Fig. 2 is a longitudinal section.

Referring to the drawings in detail, 1 and 2 denote a pair of side plates cut away so as to provide a pair of feet 3. Adjacent to one 40 of the feet 3 of each of the side plates is a notch 4 to provide means for the plates straddling the sill of a car. The plates are connected together through the medium of a series of transversely-extending bars 5, each 45 of which has both ends screw-threaded as at 6. The screw-threaded ends of the bars 5 extend through suitable openings in the plates 1, 2 and each of the screw-threaded

ends of each of the bars carries a pair of nuts indicated by the reference characters 50 7, 8, the nuts 7 being disposed against the outer face of the plates 1, 2, and the nuts 8 abut against the inner faces of the plates, the nuts 8 constituting set nuts. The intermediate bar of the series of bars is arranged 55 above the planes of the other two bars and the end bars are also arranged in different planes.

Journaled in the plates 1, 2 is a pair of rollers 9, 10. The spindles of the rollers are 60 indicated by the reference character 11, and project through the plates 1, 2. The diameter of each of the rollers 9, 10 is such that the rollers will project above the top edge of the plate. The spindles 11 are arranged in 65 horizontal alignment with respect to each other.

When using the device, the same is positioned so as to straddle the sill of the car and it will overcome a dead pull on the door 70 sill when the baggage is being drawn into the car, as the baggage traveling over the rollers 9, 10 will facilitate this movement.

When used as a truck for shifting or moving heavy burial cases or boxes, the position 75 of the device is reversed, that is to say, the rollers are brought in contact with the floor, whereas when used for removing trunks, boxes and the like from a car the rollers are uppermost.

What I claim is—

A baggage roller comprising a pair of side plates, a series of bars connecting said plates together, said bars arranged in different planes, a pair of rollers journaled in said 85 plates, said rollers projecting above the top edges of the plates, each of said plates provided with a notch to facilitate the straddling of a car sill when the device is being used.

In testimony whereof, I affix my signature 90 in presence of two witnesses.

ROBERT F. SLATER.
